UNITED STATES PATENT OFFICE.

LOUIS C. DREFAHL, OF LAKEWOOD, AND WHITFIELD R. CARSON, OF SOUTH EUCLID, OHIO, ASSIGNORS TO THE GRASSELLI CHEMICAL COMPANY, OF CLEVELAND, OHIO, A CORPORATION OF OHIO.

WATER JACKET.

Application filed December 6, 1919. Serial No. 343,095.

To all whom it may concern:

Be it known that we, LOUIS C. DREFAHL and WHITFIELD R. CARSON, both citizens of the United States, and residents of Lakewood, county of Cuyahoga, and State of Ohio, and of South Euclid, county of Cuyahoga, and State of Ohio, respectively, have jointly invented a new and useful Improvement in Water Jackets, of which the following is a specification, the principle of the invention being herein explained and the best mode in which we have contemplated applying that principle, so as to distinguish it from other inventions.

The present invention, relating, as indicated, to water jackets, is more particularly directed to the use of the improved type of water jacket in a furnace, such as is commonly used for the making of silicate of soda. Silicate of soda can be made by the fusion of sand and salt cake, but it is found that this mixture has a rapid corrosive action on the refractory material, with which the furnaces are commonly lined. This corrosive action is so rapid that it necessitates the frequent shut-down of the furnace for repairs and replacements, and greatly lowers the output of the furnace. The present invention is particularly directed to an improved type of furnace for use in making silicate of soda, which will avoid the results noted above and which will permit of a practically continuous operation of the furnace chamber through long periods of time. These improved results are secured through the use of our improved type of water jacket, and its arrangement and mounting in the furnace walls. To the accomplishment of the foregoing and related ends, said invention, then, consists of the means hereinafter fully described and particularly pointed out in the claim.

The annexed drawing and the following description set forth in detail certain mechanism embodying the invention, such disclosed means constituting, however, but one of various mechanical forms in which the principle of the invention may be used.

In said annexed drawings:

Fig. 1 is an elevation of our improved furnace partially in section, showing the general location of the water jackets; Fig. 2 is a side elevation of the jacket; Figs. 3, 4 and 5 are sections on the lines 3—3, 4—4,

and 5—5, respectively, in Fig. 2; Fig. 6 is 55 a partial side elevation of a modified construction; Fig. 7 is a section on the line 7—7, Fig. 6; and Fig. 8 is a partial transverse section through the furnace chamber showing the mounting of the water jacket 60 with respect to the walls of the furnace.

In Fig. 1 there is shown a furnace of a common type having spaced walls 1 and an arched roof 2, and being provided with a series of water jackets 3 extending around 65 the walls of the furnace. Each of these jackets 3 is provided with suitable intake conduits 4, and with outlet conduits 5, which may be connected in any desired manner of sources of supply and drain. Each 70 water jacket is also provided with manholes 6 and suitable removable covers 7 therefor. The construction of the water jacket is shown in Figs. 3 to 7, inclusive. The jacket consists of two open box-like 75 members 8 and 9, received one within the other, and welded along their over-lapping edges 10 to make a tight and integral container. Wherever there is an inlet or outlet connection the connection is formed in 80 the manner shown in Figs. 3 to 7, certain connections being indicated in Figs. 3 and 4, and consisting of a suitably formed collar 20 of sheet metal adapted to closely fit against the rounded edge of the part 9 of 85 the jacket, to which it is welded to provide a seamless joint. The same construction is used for the connections shown in Figs. 5, 6 and 7, while for all inlet connections a baffle plate 12 is provided within the jacket 90 to cause an improved spreading and distribution of the incoming water. The resulting water jacket is as nearly permanently watertight as it is possible to make it, and the single joint or seam is provided 95 on the ends, top and bottom of the jacket and at a point spaced a considerable distance from the front wall 13 of the jacket, which is next to the furnace chamber.

In Fig. 8 there is shown one wall of the 100 furnace chamber which consists of suitable refractory material. The water jackets 3 are built into this furnace wall and extend through flush with the wall of the furnace so that they are in direct contact with the 105 molten material therein.

A disadvantage of course of having a water jacket in direct contact with the mol-

ten material is that it is a source of heat loss, and to avoid any great loss the depth of the water jackets is kept as low as possible, so that in the furnace the jackets do not extend more than a few inches above the maximum height of the charge at any time during fusion. They are so mounted in the walls of the furnace as to extend a short distance above and below the flux line, at which point the greatest corrosion takes place.

It has been found that a furnace so constructed is capable of practically indefinite and continuous operation, and while a small amount of heat from the furnace is lost through the radiation of the water in the jackets, this slight loss is more than compensated for by the better action and very much longer life of the furnace chamber.

A modification of the jacket is shown in Figs. 6 and 7, in which the outlet connection is disposed at an angle, but this conduit is attached in the same manner as shown in previously described figures.

Other modes of applying the principle of our invention may be employed instead

of the one explained, change being made as regards the mechanism herein disclosed, provided the means stated by the following claim or the equivalent of such stated means be employed.

We therefore particularly point out and distinctly claim as our invention:—

In a silicate of soda furnace the combination of a furnace chamber adapted to receive and melt a mixed charge of materials, said chamber having its walls about its upper and lower portions formed of refractory material, a narrow belt of water jackets disposed at an intermediate point in the inner walls of said furnace between said upper and lower sections of refractory material, said water jacketed section being disposed in contact with the material to be melted and at the normal flux line of the molten charge and extending a slight distance above and below the same.

Signed by us, this 3rd day of December, 1919.

LOUIS C. DREFAHL.
WHITFIELD R. CARSON.
